UNITED STATES PATENT OFFICE.

FERDINAND SATTERSTROM, OF HASTINGS, MINNESOTA, ASSIGNEE TO MAGNETIC POWER TRANSMITTER COMPANY, OF FARIBAULT, MINNESOTA, A CORPORATION OF MINNESOTA.

ELECTRICAL ACTUATING MEANS FOR TYPEWRITER TYPE-BARS AND OTHER DEVICES.

1,895,599.

Specification of Letters Patent.

Patented Nov. 1, 1932.

Application filed January 31, 1929. Serial No. 356,437.

To all whom it may concern:

Be it known that I, FERDINAND SATTERSTROM, a citizen of the United States, resident of Hastings, in the county of Dakota and State of Minnesota, have invented certain new and useful Improvements in Electrical Actuating Means for Typewriter Type-Bars and other Devices, of which the following is a specification.

10 This invention relates to improvements in electrical actuating means designed particularly for operating the type-bars of typewriters, though capable of being used for operating many other key-controlled devices, such as type-setters, type-casting mechanism, and adding or calculating machines. I have described and illustrated here-in the application of the invention to typewriter bars, without limiting myself to this particular use. The general arrangement of the typewriter to which the actuating device is applied is disclosed in my pending application for Letters Patent, dated August 17th, 1917, Serial No. 186,698.

15 I design by the improvements described and claimed in this application to simplify, and make more certain in operating the actuating mechanism in my said former application.

20 It is well understood that when an electric current is broken, a spark occurs which corrodes, burns or otherwise ruins any contact excepting one made of platinum, thereby making such contact unreliable. Platinum has been found to be the only metal which will withstand, for a long period of time, the heating effect produced by the breaking of a current.

25 In devices where many make-and-break contacts are to be used, as in a typewriter, the number of contacts varying from possibly 40 to 80, as may be the case, the work and expense of supplying a separate pair of platinum contact points for each key is necessarily expensive.

30 One of the objects of this invention is to make use of only a single pair of platinum contact points for operating levers, such as type keys, whatever their number may be, acting with a universal contact forming bar located in proper relation to a keyboard.

35 The invention consists generally in a universal contact bar arranged in operative re-

lation to a pair of contact points and a series of operating keys or levers, whereby an electric circuit may be closed through said pair of contact points upon the operation of any one of said keys or levers.

40 The invention consists generally in an actuating means having a series of selecting magnets, and one or more operating magnets, the selecting magnets bringing the type-bars or other devices to be actuated, into position to be moved by the universal actuating bar, controlled by said operating magnet, a series of keys, and a universal contact bar through which the circuits for all of the magnets are controlled.

45 The invention consists further in the constructions and combinations hereinafter described and particularly pointed out in the claims.

50 In the accompanying drawings forming part of this specification,

55 Figure 1 is a plan view of the principal operative part of a typewriter embodying my invention, not including the keys and keyboard.

60 Fig. 2 is a plan view of the keyboard.

65 Fig. 3 is a plan view, partly broken away, of the keyboard and the circuit-closing devices that are controlled by the keys.

70 Fig. 4 is a longitudinal section of the keyboard taken substantially on the line 4-4 of Fig. 3.

75 Fig. 5 is an elevation and partial diagram illustrating the operative parts of the machine, showing them in positions they occupy when the machine is at rest.

80 Fig. 6 is a similar view showing the parts in position to close the actuating circuit and showing one of the type bars in the position it assumes in the printing operation.

85 Figs. 7 and 8 are details illustrating the operation of the universal contact bar, and the circuit closer.

90 In the drawings, 2 represents the frame of a portion of a typewriting machine, which furnishes support for a series of type bars 3, each of which is provided with a suitable type 4. Said bars are preferably arranged in a semi-circular group, as illustrated in Fig. 1 of the drawings. The frame 2 is preferably provided with a semi-circular plate 5 to which type supporting lugs 6 are secured. The type bars 3 are pivoted to the

lugs 6, preferably at the points 7, a short distance from the end of the type bars. A type bar actuating lever 8 is pivoted to a bracket 9 arranged on the frame of the machine. The lever 8 and the rear end of the type bar 3 are connected by a link 10. Preferably the type bars are arranged to stand normally in a nearly vertical position, with the rear ends of the type heads resting 10 against a semi-circular bearing 11, as shown in Fig. 5 of the drawings. Pivotally connected to each of the actuating levers 8 is a connecting member 12. These members are preferably in the form of bars arranged in 15 substantially vertical positions and passing through slots 13 in a slotted guide plate 14. Normally these members stand at the rear end of the slots and are preferably arranged to rest against a bar 15 extending across the 20 plate 14. The lower end of each connecting member 12 is provided with an off-set 16 to which is connected a suitable spring 17, the opposite end of the spring being suitably connected to a stationary part of the frame. 25 These springs tend to hold the connecting members 12 at all times with their rear edges against the bar 15, as shown by full lines in Fig. 5 of the drawings. The actuating levers 8 preferably extend through slots 30 in a guide bar 18, as shown in Figs. 5 and 6 of the drawings.

Each connecting member 12 is provided at its upper end, with a shoulder forming this portion of the member into a laterally 35 extending hook 19, as shown in Figs. 5 and 6.

A series of selecting magnets 20 are mounted upon suitable supports upon the frame of the machine. Each of these magnets is provided with a pivoted armature 21 extending 40 longitudinally of the magnet, and passing laterally by both poles 22 thereof, whereby when the magnet is not energized, by the passage of an electric current therethrough, the armature will stand in the position shown 45 by full lines in Fig. 5 of the drawing. The armatures 21 are connected by suitable links 23 with the connecting members 12, whereby when any armature is energized the upper end of the corresponding connecting member 50 12 will be moved from the position shown by full lines in Fig. 5 to the position shown by dotted lines in Fig. 5 and by full lines in Fig. 6.

Arranged in close proximity to the connecting members 12 is a universal actuating or power bar 24, preferably supported by arms 25 upon a rock shaft 26. As here shown the shaft 26 is mounted in bearings 31 on the machine frame 2 and has near each 55 end a crank arm 27, to which is connected a rod 28, extending to and connected with the upper end of a pivoted armature 29, arranged to coact with an operating magnet 30.

I have here shown two of the operating

magnets 30, one arranged near each side of the machine. A single operating magnet may, if preferred, be employed to move the universal power bar.

With this construction and arrangement 70 of parts, when any one of the selected magnets 20 is energized, the corresponding member 12 will be thrown forward into the position shown by dotted lines in Fig. 5 and by full lines in Fig. 6. The operating magnets 75 30 are designed to be simultaneously energized, as hereinafter described, and when these magnets are energized the rock shaft 26 will be turned through the armature 29, connecting rods 28, and crank arms 27, thereby moving upward the universal power bar 24. The movement of this bar, through the connecting member 12, actuating lever 8 and link 10, actuates the corresponding type bar 3, bringing the same into the position 85 shown in Fig. 6 of the drawings and making an impression, from the operated type, upon the paper in printing position on the machine.

For the purpose of restoring the universal 90 power bar 24, and type connected therewith, to normal position, after the printing operation, springs 32 are connected to the arms 25. These springs are put under tension when the power bar is moved by the operating magnets. When these magnets are de-energized the springs return the universal actuating bar 24, and the parts connected therewith, to normal position, and the springs 17 restore to normal position the 100 connecting members 12, the levers 8 and type bars 3.

It will be understood that each printing operation requires the energizing of the selecting magnet controlling the type bar that 105 is to be operated, and also requires the energizing of the operating magnet.

It will also be understood that the selecting magnet must first act, to move its connecting member 12 carrying the hook 19 into 110 operative position, before the universal power bar is actuated by the operating magnets.

I find that the selecting and operative magnets may both be arranged in the same 115 circuit and be energized at the same time, the selecting magnet, in that case, acting more quickly than the larger operating magnet, thereby bringing the corresponding connecting bar 12 into position to be moved by the 120 universal power bar before said power bar is moved by the operating magnet.

It is, therefore, perfectly practicable to arrange each selecting magnet in circuit with the operating magnets.

I may, however, as an alternative construction, provide independent circuits for the selecting and operating magnets, in which case, however, the movement of any key, will first close the circuit through the 130

corresponding selecting magnet, and further movement of said key will thereafter close the circuit through the operating magnets.

As the type keys and selecting magnets are all alike and operate in the same way it will be necessary to describe the construction and arrangement of only one of said keys and the arrangement of the circuit or circuits through the selecting and operating magnets controlled by said key.

Pivotaly supported upon the frame of the machine is a key lever 40 having a key top 41. These keys are arranged in any preferred manner, a convenient grouping there-
15 of being illustrated in Figs. 2 and 4 of the drawings. Arranged beneath the key levers, and extending transversely thereof, is a rock shaft 42 mounted in suitable bearings 43, 43, upon the frame of the machine. Secured to
20 this rock shaft preferably near its end, are the crank arms 44, supporting a universal contact bar 45, which connects the ends of said crank arms and is preferably formed integrally therewith. The crank arms prefer-
25 ably extend beyond the rock shaft 42, and springs 46 are connected to said crank arms and to stationary points on the machine frame. Suitable stops 44' are provided to limit the upward movement of the bar 45. These springs tend, at all times, to hold the
30 universal contact bar at the upper limit of its movement, while permitting said bar to be moved downward when pressure is applied to the upper part of said bar at any
35 point in its length.

Arranged beneath each of the key levers is a contact arm 50, preferably pivoted to a suitable insulated stationary support 51 on the frame of the machine and arranged to be held in an elevated position by a suitable
40 spring 52. An insulating block 53 is preferably secured to the under side of the key lever 40, and the contact arm 50 is normally held with its upper or forward end resting against the under side of said insulating block.

Beneath the contact bar 45 is arranged a contact spring or member 54, preferably secured upon a suitable support, the spring being preferably of substantially the form shown with its free end extending beneath the universal contact bar 45, but not in contact therewith.

A suitable plate of insulating material 55 is preferably arranged upon the frame of the machine. On this plate the supports 51 for the contact arms 50, the bearings 43 for the rock shaft 42, supporting the universal contact bar 45, and the contact spring or mem-
60 ber 54, are all supported.

I have shown the contact spring or mem-
ber 54 made double, that is to say the sheet of
spring metal of which the plate is formed is
divided longitudinally so that its end forms
65 two parallel contacts extending beneath the

universal contact bar 45. As shown in Figs. 4 and 7 of the drawings I prefer to provide a bar 56 of insulating material, supported upon the plate 55, and having arms that extend horizontally above the contact spring 54 and the spring 60 hereinafter described (see Figs. 3, 4 and 7). Adjusting screws 57 are provided in this bar extending downward therethrough with their ends above the ends of the contact spring 54. By means of these screws the normal distance between the ends of the contact spring 54 and the under side of the universal contact bar 45 may be regulated.

By dividing the contact spring so as to 80 form the two contact members as shown, these ends may be adjusted so that one stands a little closer to the contact bar than the other. With this arrangement the contact will first be made between the under surface 85 of the contact bar and the portion of the contact spring that stands nearest thereto.

Should, however, the surface of this contact member become corroded by the sparking which will take place whenever the contact bar is moved away from the contact spring, after a circuit has been closed, so that the circuit through said contact is not properly closed, the further depression of the universal contact bar will bring its under 95 surface into contact with the other end of the contact springs, thus insuring a proper closing of the circuit.

I have also shown a second contact spring 60, preferably in all respects like the contact 100 springs 54, and arranged in similar relation to the universal contact bar 45. Adjusting screws 61 are preferably arranged in connection with the contact spring 60 in the same way and for the same purpose that the 105 screws 57 are arranged in connection with the contact spring 54.

The preferred arrangement of electrical connections and circuits is as follows: D represents a suitable battery; A is a circuit wire 110 extending from the contact spring 54 to the battery D, which has a ground connection at E. C is an electrical connection between a selective magnet 20 and a corresponding contact arm 50. Each magnet 20 has a 115 ground connection at F. B is an electrical connection between the contact spring 60 and the operating magnet 30. The operating magnet 30 has a suitable ground connection at G.

I have shown the contact spring 60 ad-
justed so that it stands a little farther away from the universal contact bar 45 than does the contact spring 54. With this arrange-
ment when any key 40 is depressed the cor-
responding contact arm 50 will come in con-
tact with the universal contact bar 45 at 125 some point in its length, and will depress said bar until its lower surface comes in contact with the contact spring 54. An elec- 130

tric circuit will then be closed from the battery D through the wire A through the contact spring 54, the contact bar 45, contact arm 50, and wire C to magnet 20. The battery D and the magnet 20 being respectively grounded at E and F, the circuit through the magnet will be completed, the magnet will be energized and the connecting bar 12 will be moved into the position shown by dotted lines in Fig. 5 and full lines in Fig. 6. A further depression of the universal contact bar 45 will cause the circuit through the operating magnet 30 to be closed, as follows: from battery D through connection A 15 through contact spring 54; through universal contact bar 45 to contact spring 60; through contact spring 60 and connection B to magnet 30. This magnet being grounded at G and the battery being grounded at E the circuit will be complete through the magnet 30, which will then be energized and will operate the universal actuating bar 24, causing the type bar whose connecting rod 12 has been moved by the corresponding selective magnet 20 into actuating position, to be operated and thereby to impress its type upon the paper.

As I have already stated it makes no difference whether the selecting magnet is energized before or simultaneously with the energizing of the operating magnet, and in either case the selective magnet will perform its work first.

If the contact springs 54 and 60 are at the same distance from the under side of the universal contact bar 45 both magnets will be energized at the same time. If, however, the contact spring 54 is a little nearer the contact bar than the spring 60, the selecting magnet will be energized first, and the operating magnet will be energized as soon thereafter as the contact bar 45 comes in contact with the contact spring 60.

Fig. 8 shows electrical connections A and B with the contact spring 54, thereby causing the simultaneous energizing of the magnets 20 and 30, through the battery D, connection A, bar 45, lever 50, block 51, connection C to magnet 20, ground F and E, and through battery D, connection A, spring 54, connection B, magnet 30, ground G and E completing the circuit. Suitable escapement connection (not shown) may be attached to the shaft 26 to move the carriage after each operation of the key, and to accomplish the same result when spacing bar is used, I provide at each end of the keyboard a lever 40' connected with the spacing bar 41'. Whenever said bar is depressed the levers 40' will 60 through levers 50, bar 45 and springs 54 and 60 make a circuit through the magnet 30 and rock the shaft 26 to work the escapement connection for spacing. The selecting magnets are not used with the spacing bar.

Suitable springs 46' are provided to hold the spacing bar in its raised position.

I have not thought it necessary to illustrate and describe other features of typewriting machines such as the carriage operating mechanism, the paper support, the inking ribbon and its supporting and feeding means as my invention does not extend to these features of a typewriter, and my present invention may be used in connection with other typewriting mechanisms of any suitable or preferred construction.

The mechanism herein described for operating the type-bar actuating levers is capable of use for a variety of purposes, such as operating the actuating levers of adding or calculating machines, and such structures are considered to be within the scope of the specification and claims herein.

It is obvious that the details of construction and arrangement of parts may be varied in many particulars without departing from my invention.

I claim as my invention:

1. The combination, with a series of actuating levers, of a series of selecting magnets, and an operating magnet, each selecting magnet, when energized, serving to bring the corresponding actuating lever into position to be moved by the operating magnet, a series of keys corresponding to the actuating lever, each provided with a contact device, and a universal contact bar, movably supported and arranged to be operated by any key, each key serving, when operated, to first bring its contact device into connection with said contact bar, and thereafter to move said bar to close an electrical circuit through said bar, the operating magnet and the selecting magnet corresponding to the operated key.

2. Actuating means for type bars of typewriting machines comprising, in combination, a series of actuating levers, a selecting magnet for each actuating lever, operating magnets common to all of said levers, a contact member having electrical connection with said magnets, a universal contact bar arranged to be brought into engagement with said contact member, a key lever for each actuating lever, a contact device in operative relation to each key lever, and each arranged to make an electrical connection with said universal contact bar and to move said bar into engagement with said contact members, and complete an electric circuit through the corresponding selecting magnet and through the operating magnet.

3. In a typewriting machine, the combination with a series of type bars, of a universal power bar therefor, connecting members for said type bars, arranged to be brought into operative relation to said universal power bar, a selecting magnet for

each of said type bars; an operating magnet for moving said universal power bar, keys corresponding to said type bars, contact members having electric connection with 5 said selecting magnets and also with said operating magnet, a universal contact bar, and a circuit closing contact device for each key lever, whereby upon operation of any key lever its contact device is first brought 10 into electrical connection with said universal contact bar and said bar is thereafter brought into engagement with said contact members, and the corresponding selecting magnet, and the operating magnet are energized, for the purpose set forth.

4. In a typewriting machine, the combination, with a series of type bars, of a selecting magnet for each type bar, operating magnets common to all said type bars, 20 contact members having electric connections with all magnets, a universal contact bar arranged to be brought into contact with said contact members, a key lever for each type bar, and contact means for each lever 25 arranged to move said universal contact bar into engagement with said contact members, whereby upon the operation of any key its contact means is first brought into electrical connection with said contact bar and a circuit, through said universal contact bar is thereafter completed through the corresponding selecting magnet and the operating magnet.

5. In a typewriting machine the combination, with a series of type bars, of a selecting magnet for each type bar, operating magnets common to all said type bars, contact members having electric connection with said magnets, a universal contact bar

arranged to be brought into engagement 40 with said contact members, a key and key lever corresponding to each type bar, a contact device in operative relation to each key lever, each contact device being arranged to make an electric connection with said 45 universal contact bar, and to move said bar into engagement with said contact members, whereby, upon the operation of any key, said universal contact bar is moved into engagement with said contact members and 50 completes an electric circuit through its corresponding selecting magnet and through the operating magnets.

6. The combination with a series of magnets, of a corresponding series of operating 55 keys, each provided with a contact device, a universal contact bar movably supported and arranged to be operated by any key, each key serving, when operated, to first bring its contact device into electrical connection with said contact bar, and thereafter to move said bar to close an electrical circuit through said bar, and the magnet corresponding to the operated key.

7. The combination with a series of magnets, of a corresponding series of operating 65 keys, each provided with a contact device, a universal contact bar, and means for causing each key, when operated, to first bring its contact device into electrical connection 70 with said contact bar, and thereafter to close an electrical circuit through said universal contact bar, said lever contact device, and the magnet corresponding to the operated key.

In witness whereof, I have hereunto set my hand this 9th day of January, 1920.

FERDINAND SATTERSTROM.
